(57) **CLAIM**

The ornamental design for broom, as shown and described.

DESCRIPTION

1. Broom

1.1 is a top, front and right side perspective view of a broom;

1.2 is a top, rear and left side perspective view thereof;

1.3 is a front view thereof;

1.4 is a rear view thereof;

1.5 is a right side view thereof;

1.6 is a left side view thereof;

1.7 is a top view thereof;

1.8 is a bottom view thereof;

1.9 is an enlarged bottom view thereof; and

1.10 is a further enlarged bottom view thereof.

The broken lines shown in 1.9 and 1.10 are included for the purpose of illustrating the environmental structure and form no part of the claimed design.

1 Claim, 10 Drawing Sheets
